(57) **CLAIM**

The ornamental design for a nozzle storage box, as shown and described.

DESCRIPTION

FIG. 1 is a top, front, and left side perspective view of a nozzle storage box showing my new design.

FIG. 2 is a bottom, rear, and left side perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines in the figures depict portions of the nozzle storage box that form no part of the claimed design.
